Inventor:
Arthur W. Clauder,
by *Myron F. Lunt*
His Attorney.

Patented July 17, 1928.

UNITED STATES PATENT OFFICE.

ARTHUR W. CLAUDER, OF BRIDGEPORT, CONNECTICUT, ASSIGNOR TO GENERAL ELECTRIC COMPANY, A CORPORATION OF NEW YORK.

ROTARY SWITCH HANDLE.

Application filed November 1, 1924. Serial No. 747,396.

The present invention relates to thumb pieces or handles of electric switches.

In electric switches of the rotary type, it is common practice to provide a plate or cover to enclose the active parts thereof and to hold such cover or plate in position by constructing the operating handle or thumb piece to bear yieldingly against the outer surface thereof and force it against the switch base. The handle or thumb piece is customarily attached to the switch shaft by screw threading it upon the outer end of the latter, and, on account of the ease with which a child may unscrew the usual thumb piece or handle and remove the protective enclosure means of the electrically charged parts, there has arisen a demand for something safer and better suited to domestic use.

The object of my invention is the provision of an improved handle or thumb piece for rotary switches which may not be detached from the switch except by the use of a special tool or key, which shall be composed of few and sturdy parts and which may be manufactured at low cost.

One embodiment of the invention is shown in the accompanying drawing in which Fig. 1 is a vertical section of the handle and a fragmentary sectional representation of the switch and protective enclosure; Fig. 2 is a transverse section of the handle at line 2—2, Fig. 1, and Fig. 3 is a perspective representation of certain detail parts.

The outer or main part 1 of the handle is of moulded insulating material such as compound or porcelain with the exterior surface substantially cylindrical, with longitudinal flutes 2 to provide a good handhold thereon and interiorly it is provided with a cylindrical chamber 3 open at the lower end and having an axial opening 4 at the upper end with a countersunk portion 5.

Within the chamber 3 is a metal thimble 6 of a shape and size to substantially fill the space therein and project somewhat beyond the lower surface of the main part of the handle. The inner side walls of the thimble have three spaced longitudinal ribs 7 formed by indenting the metal. The upper end wall is apertured centrally corresponding to the axial opening 4 in the main part and anchorage teats 8 are struck upwardly for engagement with corresponding depre-

sions in the upper end wall of the chamber 55

An eyelet 9 is assembled in the end aperture of the thimble 6 with its flange 10 engaging the inner surface of the end wall thereof, and upon passing the upper end through the axial opening 4 and spinning it over the shoulder formed between the opening 4 and the countersink 5 the thimble is held securely in the main part 1 and a passageway through the eyelet 9 is provided for the insertion of a tool whereby the handle may be disconnected from the switch.

Within the shell 6 is a nut or internally threaded cylinder 11 adapted to be screwed upon the end of the operating spindle or shaft 12 of an ordinary rotary switch and in its upper end is a cleft or notch 13.

A disk 14 having spring ratchet arms 15 struck downwardly therefrom and a central aperture crossed by a bar 16 is assembled on the upper end of the cylinder 11 with the bar 16 in the cleft 13 and is secured thereto by lugs 17 struck up from the outer surface of the cylinder.

A combined guide and stop disk 18 having a central aperture 19 of a size to loosely receive the cylinder 11 and radial arms 20 with notches 21 in their outer ends corresponding to the longitudinal ribs 7 of the thimble 6 is assembled upon the cylinder 11 adjacent the ratchet disk 14 with the ratchet arms 15 adapted to engage at their free ends against the side edges of the radial arms 20.

A helical spring 22 is assembled about the cylinder 11 and thrusts against the guide and stop disk 18 at its upper end and at its lower end against a guide washer 23 assembled about the lower end of the cylinder 11 and filling the lower end of the thimble 6 to which it is secured by spinning over the metal thereof and forming an external beaded collar 24 thereon adapted to engage the upper surface of the switch cover 25.

In the operation of screwing the handle upon the switch shaft in the usual right-handed direction, the nut or threaded cylinder 11 is caused to rotate with the main or outer part 1 by reason of the engagement of the radial arms 20 of the combined guide and stop disk 18 rotatably fixed to the latter with the free ends of the ratchet arms 15 rotatably fixed to the former, and as the nut is screwed home on the switch shaft, it is drawn downwardly against the tension of

the spring 22 out of the thimble, the latter of which is arrested by its engagement with the switch cover 25.

In case of an attempt being made to unscrew the handle by rotation thereof in the usual left-handed direction, the main or outer part 1 will merely swivel on the nut or threaded cylinder 11, since the radial arms 20 are free to pass beneath the spring ratchet arms 15. However, a proper tool or key may be entered through the eyelet 8 and into direct engagement with the cleft 13 in the nut and the latter turned independently of the main part of the handle.

15 While I have shown and described the best embodiment of the invention known to me, I do not desire to be restricted thereto.

What I claim as new and desire to secure by Letters Patent of the United States, is:

20 1. A handle for rotary switches comprising a main part chambered at one end, a cylindrical metal thimble secured in the chamber of said main part and provided with internal ribs or shoulders, a combined stop and guide disk freely engaging said ribs or shoulders, a switch engaging nut assembled within said thimble and axially guided therein by said guide and stop disk and in which it is journalled, a ratchet secured to said nut and normally engaging said guide and stop disk, a spring forcing said nut inwardly of said main part, and means in said thimble for retaining said spring in place.

25 30 35 2. A handle for rotary switches comprising a main part chambered at one end and axially apertured at the other end, a cylinder

drical metal thimble provided with internal ribs extending longitudinally thereof and assembled within the chamber of said main part, an eyelet located in the aperture of said main part and rigidly connecting said thimble thereto, a combined guide and stop disk mounted for longitudinal movement on said internal ribs, a switch engaging nut assembled within said thimble and journalled in said guide and stop disk and provided with a cleft in the upper end thereof, a ratchet disk secured in said cleft end of said nut, a spring normally holding said guide and stop disk in engagement with said ratchet disk and forcing said nut inwardly of said main part, and means on said thimble for retaining said spring in place.

3. A handle for rotary switches comprising a main part chambered at the lower end and axially apertured at the upper end, a switch engaging nut in the chamber of said main part provided with a cross slit in the upper end thereof, a ratchet disk having a central bar assembled in the slit of said nut, a combined guide and stop disk movable longitudinally in the chamber of said main part and in which said nut is journalled, a spring normally tending to force said disks into engagement and said nut inwardly of said main part, and a washer secured in the outer end of said chamber and operating as a fixed guide for said nut and as a retaining means for said spring.

In witness whereof, I have hereunto set my hand this 28th day of October, 1924.

ARTHUR W. CLAUDER.
